PUMPING APPARATUS

Gale L. Ferguson, Euclid, Ohio, assignor to
Westco Pump Corporation, Davenport, Iowa, a
corporation of Delaware

Application August 21, 1931, Serial No. 558,455

1 Claim. (Cl. 103—96)

This invention relates to rotary pumps, and more particularly to pumps comprising a rotor having a liquid impelling means such as a plurality of peripheral buckets operating in a liquid passage, and is a continuation in part of my co-pending application, Serial No. 438,465, filed March 24, 1930 and is a continuation in part of my copending application Ser. No. 458,437, filed May 31, 1930.

10 One of the objects of the present invention is to provide simple and effective means for priming a pump of the rotary type having a pressure developing passage and a rotor cooperating therewith.

15 Another object is to provide a rotary pump which is self-priming at all times, regardless of the time interval elapsing between the periods of use.

20 A further object is to provide a compact pumping apparatus of the rotary pressure building type which can be primed with a minimum of liquid and in which the elements comprising the priming mechanism require a minimum of space.

25 Another object is to provide a rotary pump with self-priming means of such construction that the priming liquid enters the pressure developing passageway through a passage or passages other than the outlet port of the pressure developing passageway.

30 A further object is to provide a rotary pump having a pair of mating pump rings that form a pressure building passageway with priming passages independent of the outlet that lead back to the pressure developing passageway through 35 the pump casing and mating pump rings.

A still further object is to provide a rotary pump with the pressure passageway-forming rings of new and improved construction.

With the above and other objects in view which 40 will be apparent from the following detailed description, the present invention consists in certain features of construction and combinations of parts which will be readily understood by those skilled in the art to which the invention appertains.

In the drawings which illustrate suitable embodiments of the invention,

Figure 1 is a side elevation of a rotary pump having the priming means incorporated therein, a portion of the pump casing being broken away to show the construction of the interior of the pump;

Fig. 2 is a transverse section taken substantially on the line 2—2 of Fig. 1;

Fig. 3 is a horizontal section taken substantially on the line 3—3 of Fig. 2;

Fig. 4 is an exploded top plan view of the pump rings and rotor showing the inlet, outlet and priming ports of the pump rings;

5 Figs. 5 and 6 are perspective views of one of the pump rings, showing the passages in the opposite sides thereof;

Fig. 7 is a fragmentary section showing a modified construction of the return passages; 10

Fig. 8 is a section taken substantially on the line 8—8 of Fig. 7; and

Fig. 9 is a fragmentary section showing a further modified construction of the outlet portion of the pump.

15 Referring to the accompanying drawings in which like numerals refer to like parts throughout the several views, the pump casing 1 which is mounted on a suitable base 2 is provided with an inlet stub 3 and an outlet stub 4 having suitable 20 connections, here shown as internal screw threads, for receiving inlet and outlet conduits respectively. The casing is formed with a central bore 5 therein into which the passageways of the stubs 3 and 4 open. The bore 5 is closed in with a 25 cover plate 6 which is secured to the casing by suitable cap screws 7.

A pair of pump rings 8 and 9 are mounted 30 within the bore 5 and are provided with mating annular grooves or channels 10 and 11, respectively, which, when the rings are in position in the bore, form a pressure developing passageway A. The ring 8 is formed with a circumferential flange of greater depth than the inner flange and which engages with the outer flange of the other 35 pump ring 9, to close the passageway therein and to provide a space between the inner flanges of the two rings for the reception of the pump rotor 12.

Each ring is formed, as shown in Figs. 4, 5 40 and 6, with a recess that opens into the groove thereof and which combines with the corresponding recess of the other ring to form an outlet port 13 that communicates with the outlet passage 14 formed in the outlet stub 4.

45 In order to insure that the fluid flowing into the pump will enter the pressure developing passageway A at both sides of the impeller 12, a divided inlet is provided. This is accomplished by forming a port 15 in the ring 8 and a recess 50 16 in the ring 9 which open into the ring grooves 10 and 11, respectively, and which communicate with the inlet passage 17 formed in the inlet stub 8.

55 As shown in Figure 5, each ring is formed with

a stop means 24 between the inlet and outlet ports which engages with the sides of the impeller buckets and the widened flange of the ring 8 is also formed with a segmental portion 25 that 5 engages with the periphery of the impeller. These stop means and segmental portion block off the pressure developing passageway in order that the fluid being pumped will be discharged through the outlet passageway.

10 The rings are held in their proper relative position within the casing bore by means of a suitable pin 18 that extends through recesses 19 formed in the outer circumferences of the ring, and which extends into an opening formed in 15 the casing 1, as shown in Fig. 2.

The impeller 12 is mounted on a suitable shaft 20 that is journaled in the casing 1. Suitable packing 21 is carried by the casing which is held in position by a suitable packing ring 22. The 20 impeller is formed with a plurality of marginal buckets 23, alternately formed on its periphery which lie within the pressure developing passageway A, and the inner flanges of the pump rings engage with the impeller radially inwardly of 25 the buckets 23 with a running fit to substantially prevent the leakage of fluid radially inwardly of the pressure developing passageway A.

It is to be noted that the main discharge passage that leads to the pressure developing passageway is of lesser diameter than the internally threaded bore of the outlet stub, and thereby provides a shoulder 26 between the walls of the threaded bore and the passage 14. As shown in 30 Figs. 1 and 2, a pair of liquid return passages 27 35 are formed through the peripheral wall of the casing substantially parallel to the outlet passage 14, and open into the space above the opening of the passage 14 between the walls of the threaded bore and the passage 14. These passages 27, of which there may be one or more, form 40 liquid return means for conducting liquid back to the pressure developing passageway for priming purposes. Each return passage 27 communicates with the pressure developing passageway 45 through the sides of the pump rings 8 and 9. Each ring is formed with a small aperture 28 through the bottom of its groove which leads to the outer side of the ring and communicates with a circumferentially arranged recess 29 in the outer 50 side of the ring. The recess 29 of the inner ring 8 is closed in by the inner wall of the casing 1, and the recess 29 of the outer ring 9 is closed in by the cover plate 6 which contacts with the surface of the ring 9. The circumferential walls 55 of the rings 8 and 9 are notched out at 30 to place the recess 29 in communication with the downwardly extending return passages 27.

The apertures 28 are positioned in advance of the stop means preferably adjacent the outlet port 13. Considerable variation in the location of these apertures is possible, depending on such factors as the speed of the impeller and pump passageway sizes. But it has been found in 60 passages of the character shown in the drawings, 65 that the most effective results are obtained when the apertures are formed adjacent the outlet port 13. Thus, the water which is returned for priming purposes, as will be more fully described, follows a much shorter circuit than is the case 70 in pumps where the water is returned adjacent the inlet. By the term "adjacent the outlet" hereinafter used, it is understood that this means a position removed from the main outlet port in a direction opposite to the direction of rotation 75 of the impeller. The enlarged threaded bore and

the shoulders 26 permit a conduit having an internal diameter slightly larger than the passage 14 to be employed, and still provide a means whereby the water being discharged may flow back through the return passage 27 into the pressure developing passageway A.

In starting the pump, a small amount of water already being present in the pressure channel or having been originally introduced through a suitable priming plug (not shown), the water is expelled through the outlet passage 14, but being insufficient in quantity to pass out as a solid stream, some of the same passes through the return passages 27 into the pump ring recess 29. The movement of the impeller past the apertures 28 sets up a suction in the recess 29 which adds to the gravitational effect in returning the liquid through these passages into the pressure developing passageway A. The small sizes of the passageways has a tendency to aid in the separation 20 of the liquid from air, it being understood that in the priming states the proportion of air to water will be relatively high in the pressure developing passageway and in the inlet and outlet passages. In effect then, the impeller sets up an 25 efficient circulation of liquid through the limited return passages. Even with a small quantity of priming fluid a sufficient quantity is collected to start the priming effectively and cause a suction 30 which extends back through the pressure developing channel and into the inlet passage and supply pipe. By reason of the elevated position of the inlet stub 3, it will be apparent that some 35 water will always be present in the pump after the original starting, but by reason of the priming means here described the pump will be effective even if the amount of water so retained has been materially reduced by evaporation or leakage.

The pump rings 8 and 9 are provided with 40 apertures 40 through which the pressure developing passageway A communicates with the interior portion of the casing outside of the pump rings. These apertures are preferably arranged at or substantially adjacent the bottom portion of the 45 pump rings and provide means for permitting the water in chambers surrounding the pump rings to pass into the pressure developing passageway when the pump is started, affording more water for priming purposes and also to drain the pump 50 when it is desired to do so.

In Figs. 7 and 8 of the drawings a modified type of liquid return passages is shown. In this construction the outlet portion of the casing immediately above the pump rings is formed with a 55 narrow shelf portion 31, the sides of which are formed with grooves 32 leading down to the notched portions that open up the recesses 29.

In some cases it will be desirable to form a sort of retaining pocket for the liquid being discharged through the outlet stub. One means of accomplishing this is shown in Fig. 9, wherein an upwardly extending tube 33 is seated within the outlet passage 14. It will be noted in this construction that a quantity of water will be maintained around the tube 33 which can only return 60 to the pressure developing passage through the return passage 27.

It has been proved by test that the pressure 70 in the pressure developing channel is greater at the outlet than at the points where the priming liquid re-enters the pressure developing channel, and that as a result the liquid will maintain a positive circulation through the return passages 75

without these return passages acting as water discharge passages.

It is apparent from the drawings and foregoing description that an improved rotary pump is provided in which the priming is automatic and occurs regardless of how frequently the pump is used.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claim.

What I claim is:

In a rotary pump, a casing having a central bore, a pair of pump rings disposed within said bore, a cover plate clamping said rings against

each other and against the end wall of said bore, each of said rings having an annular channel therein facing the other to form a pressure developing passageway, said passage having inlet and outlet ports and stop means between said ports, said casing having inlet and outlet passages communicating with said inlet and outlet ports, and an impeller between said rings and having side opening peripheral buckets at each side thereof extending into said passageway, said rings having liquid return ports through the walls thereof near said outlet port and liquid return grooves in their outer sides closed in by said cover plate and end wall and communicating with said liquid return ports, said casing having liquid return passages in the body thereof opening into said outlet passage and into said liquid return grooves.

GALE L. FERGUSON.
